UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC TRAIN CONTROL.

1,243,782.

Specification of Letters Patent.

Patented Oct. 23, 1917.

Application filed April 1, 1916. Serial No. 88,254.

To all whom it may concern:

Be it known that I, WALTER V. TURNER, a citizen of the United States, residing at Wilkinsburg, in the county of Allegheny and 5 State of Pennsylvania, have invented new and useful Improvements in Automatic Train Controls, of which the following is a specification.

This invention relates to automatic train 10 control systems, and more particularly to the type employing electric track circuits.

It is highly desirable where electric train 15 control systems are employed, that the controlling track circuit for same be arranged on the so-called normally closed circuit principle, so that if the circuit is broken from any cause or if there is a failure of current, the train apparatus will be operated in the 20 same manner as if the track circuit were opened automatically when a danger condition exists.

It has been proposed to employ continuous 25 conductors along the track in which the circuit is normally closed but this requires considerable current, insulation of the rails or 30 conductors, and might interfere with the operation of the well-known automatic electric block signal system where such a system is installed.

35 The principal object of my invention is to provide an electric train control system operating on a normally closed circuit, in which short conductor sections can be employed.

40 In the accompanying drawing, Figure 1 is a view, mainly in section, of a train control apparatus embodying my invention and Fig. 2 a diagrammatic view of the track circuit arrangement for controlling the train control apparatus.

According to my invention at the desired 45 block intervals along the track, there is provided a rail section 1, as shown in Fig. 1, which is insulated from the ground and is connected to a source of current 2 which is normally grounded at 3 through the normally closed switch 4.

The train is equipped, as shown in Fig. 2 of the drawing, with a downwardly projecting shoe 5 which is adapted to engage the successive conductor sections 1 as the train moves along the track. The shoe 5 is arranged to be moved upwardly by engagement with a rail section 1 and at the same

time electric contact is made for completing 55 a circuit from the rail through a magnet 6 to a ground 7.

The vertical movement of the shoe 5 is adapted to actuate a valve 8 for effecting the operation of a valve mechanism which 60 in turn operates to cause an application of the brakes, but if the rail 1 is energized, the magnet 6 will also be energized and, as will be explained, this prevents the operation 65 of the brake applying valve mechanism.

The brake controlling valve mechanism may comprise a casing 9 having a piston chamber 10 containing a piston 11 and a valve chamber 12 containing a slide valve 70 13. The valve chamber 12 is connected to a source of fluid under pressure, preferably the main reservoir 14 and is adapted upon operation to vent fluid from the brake pipe 15 to effect an application of the brakes in 75 the usual manner.

A passage 16 leads from piston chamber 10 to a differential piston device having piston heads 17 and 18, and the piston chamber at the outer face of piston head 18 is 80 connected by a passage 19 to a double beat valve device having valves 20 and 33 which is controlled by the magnet 6.

The shoe 5 is secured to a vertically movable plunger 22 mounted in a casting 21 and 85 the plunger is provided with a cam portion 23 adapted to engage the roller 24 of a rocker arm 25.

The valve 8 is provided with a stem 26 adapted to be operated by the rocker arm 90 25 for venting fluid from a pipe 27 to the atmosphere.

Pipe 27 is connected to a branched passage 28, having one branch controlled by the piston head 17 and having the other branch 95 leading to the piston chamber at the face of piston head 17.

In operation, fluid under pressure is supplied from main reservoir 14 through pipe 29 to valve chamber 12 and flows through 100 port 30 in piston 11 to piston chamber 10. Fluid also flows from piston chamber 10 through passage 16 and annular passage 31 to passage 28 and thence to the face of piston head 17.

A passage 32 leads from valve chamber 12 to chamber 34 containing valve 20 and also to the piston chamber containing pis-

ton 18 and when the piston 18 is in its outer position, as shown, said passage 32 is connected through pipe 35 with a trip valve timing reservoir 36.

- 5 In the normal release position of slide valve 13, a cavity 37 connects passage 38 leading to an application valve timing reservoir 39 with an exhaust port 40 and fluid is supplied from the main reservoir 14
- 10 through valve chamber 12, passage 41 and pipe 42 to the usual feed valve device of brake valve 43, so that the supply of fluid for maintaining the brake pipe pressure in the running position of the brake valve is controlled by the application valve device.
- 15

- The stem connecting the double beat valves 20 and 33 has a piston fit in the inner closing bushing, but is provided with a small port 44 which connects passage 19 with exhaust port 45 when valve 33 is open, so that the outer face of piston 18 is normally at atmospheric pressure.
- 20

- When the shoe 5 passes over a contact section 1, if switch 4 is opened on account of a danger condition, or if the track circuit is broken or current fails, the magnet 6 will not be energized and the differential piston device will therefore remain in its normal position, but the shoe 5 will be raised by engagement with the contact section 1 so that the valve 8 is lifted from its seat and fluid is vented from pipe 27.
- 25

- Since pipe 27 is connected through passage 28, annular passage 31 and passage 16 with piston chamber 10, fluid will be vented from said chamber and the piston 10 then operates the slide valve 13 so as to connect brake pipe 15 through a cavity 46 with exhaust port 40. Fluid is therefore vented from the brake pipe to effect an application of the brakes in the usual manner. At the same time, the slide valve 13 blanks passage 41, so that the supply of fluid from the main reservoir to the brake valve is cut off and the brake valve is thus prevented from supplying fluid to the brake pipe.
- 30

- Cavity 37 in slide valve 13 also connects passage 38 with a passage 47, so that after the vent valve 8 closes when the shoe 5 leaves the contact section 1, the piston 11 will be held in application position for a predetermined period of time, until the timing reservoir 39 has been charged with fluid under pressure, by flow from the valve chamber 12 through port 30, to a pressure substantially equal to that in valve chamber 12, when the spring 48 will return piston 11 and slide valve 13 to release position.
- 35

- When the slide valve 13 is shifted to release position, the feed valve passage 41 is again connected to the valve chamber 12 and the main reservoir 14, so that the brake valve 43 operates to recharge the brake pipe and thus effect the automatic release of the brakes.
- 40

If the switch 4 is closed when the shoe 5 passes over a contact section 1, then current is supplied to energize the magnet 6 and this causes the operation of the double beat valve so as to close the valve 33 and open valve 20.

45

The opening of valve 20 permits the flow of fluid from valve chamber 12 through passage 32 to passage 19, so that the outer face of piston head 17 is subjected to fluid under pressure. At the same time, fluid is vented from the face of piston head 17 through pipe 27 and vent valve 8, so that the differential piston device is shifted to cut off communication from the passage 28 to passage 16. It will thus be seen that while the vent valve 8 is opened as before by the vertical movement of shoe 5 in passing onto the contact section 1, fluid will not be vented from piston chamber 10, so that in this case the brakes will not be applied, since the application piston will remain in release position. The movement of the differential piston is assisted by the venting of fluid from the face of piston head 17 through passage 28 and pipe 27.

50

In order to prevent possible movement of the differential piston device to normal position before the contact shoe has passed off the contact section 1, the trip valve timing reservoir 36 has been provided, which is connected through pipe 35 with the chamber at the outer face of piston head 18 when said piston head is moved to its inner position. Since this reservoir is charged with fluid from the main reservoir, as previously described, the differential piston will be maintained in its cut out position for a predetermined period of time, depending upon the rate at which the reservoir is exhausted through passage 19 and the port 44 when the valve 33 is returned to its open position upon deenergization of magnet 6.

55

It will now be apparent that with the present construction, the amount of current required for operation is reduced to a minimum, since only short contact sections are employed, while by providing normally closed track circuits, any failure will be on the side of safety. It will always be noted that the system does not require a source of current on the train, which has obvious advantages in the way of reducing the cost of maintenance and in simplifying the train apparatus.

60

Having now described my invention, what I claim as new and desire to secure by Letters Patent is:—

1. In an automatic train control system, the combination with a brake pipe, a reduction in pressure in which is adapted to effect an application of the brakes and valve device for venting fluid from the brake pipe, of a valve adapted to be operated mechanically by means along the track for varying the fluid pressure on said valve device, a

valve mechanism for controlling communication from said valve to said valve device, and means responsive to an electrical condition along the track for effecting the operation of said valve mechanism to cut off said communication.

2. In an automatic train control system, the combination with a valve device for effecting an application of the brakes, of a valve adapted to be operated mechanically by means along the track for varying the fluid pressure on said valve device, a valve mechanism normally providing communication from said valve to said valve device, and a magnet controlled valve adapted, upon energization of its magnet through a track circuit, to effect the operation of said valve mechanism to thereby cut off communication between said valve and said valve device.

3. In an automatic train control system, the combination with a valve device operated by a variation in fluid pressure for effecting an application of the brakes, of a mechanically responsive means for varying

the fluid pressure on said valve device, a piston device for controlling communication through which the fluid pressure is varied, and electro-responsive means for supplying fluid to one side and for venting fluid from the other side of said piston device to operate the same and cut off said communication.

4. In an automatic train control system, the combination with a valve device operated by a variation in fluid pressure for effecting an application of the brakes, of a mechanically responsive means for varying the fluid pressure on said valve device, a piston device for controlling communication through which the fluid pressure is varied, electro-responsive means for supplying fluid to one side and for venting fluid from the other side of said piston device to operate the same and cut off said communication, and means for maintaining said piston device in its cut off position for a predetermined period of time.

In testimony whereof I have hereunto set my hand.

WALTER V. TURNER.
